UNITED STATES PATENT OFFICE.

EMANUEL WOODINGS, OF OAKMONT, PENNSYLVANIA, ASSIGNOR TO WOODINGS FORGE & TOOL COMPANY, OF VERONA, PENNSYLVANIA, A CORPORATION OF PENNSYLVANIA.

RAIL ANCHOR.

Application filed May 19, 1926. Serial No. 110,154.

This invention relates to devices for preventing the longitudinal creeping of railroad rails. Such devices are commonly known as rail anchors, rail stays, anti-creepers, creep checks, and the like. More specifically this invention relates to rail anchors comprising a single piece of resilient steel adapted to be distorted to permit moving to gripping position on a rail base, and to secure when so positioned a positive grip with an edge contact with the under side of the rail, maintained by resiliency of the body of the anchor.

Among the objects of the invention are to provide a simple, economical, one-piece, self-locking rail anchor which will grip the rail base with great tenacity, which will hold its grip due to resiliency of the metal distorted within its elastic limits by placing the anchor on the rail, and which may be manufactured from bar steel by die forging operations.

A further object is to so shape and bend the body of the anchor that the necessary distortion thereof for securing it in place on a rail base may safely occur, and so that the several contacting portions of the anchor may be properly positioned with respect to the rail by spring pressure of the resilient anchor body.

A further object is to provide an anchor having portions adapted to contact with the under side of the rail at their edges or corners only, such contacts being preliminarily maintained by resiliency of the anchor body.

Other objects and advantages will be apparent from the following specification.

This application is in part a continuation of a previously filed application Serial Number 89,069, filed February 18, 1926.

In the drawings, Fig. 1 is a side elevation of a rail R and supporting tie T, with a rail anchor A in operative position on the rail; Fig. 2 is a partial vertical section through the rail, with a side elevation of the anchor A applied thereto; Fig. 3 is a partial vertical section on the line III-III of Fig. 2; Fig. 4 is a partial vertical section showing a modified anchor B; Fig. 5 is a view similar to Fig. 1, showing a further modification in an anchor C; Fig. 6 is a view similar to Fig. 2, showing a modified anchor D; Fig. 7 is a cross section through the anchor D on the

line VII-VII of Fig. 6; Fig. 8 is a section of anchor D on the line VIII-VIII of Fig. 6; Fig. 9 shows a side elevation of another modified anchor E applied to a rail; Fig. 10 shows still another modified anchor F in side elevation applied to a rail; Fig. 11 is a partial section of anchor F on the line XI-XI of Fig. 10; Fig. 12 shows still another modified anchor G in side elevation on a rail; Fig. 13 is a partial section on the line XIII-XIII of Fig. 12; and Fig. 14 is a partial vertical section on the line XIV-XIV of Fig. 12.

Referring to the drawings, Fig. 2 shows one form of my rail anchor applied to the base of a standard rail R. The anchor as a whole is designated by the letter A. The rail is shown in section, and comprises the usual web W. The two sides of the rail base as divided by the web are designated by letters *x* and *y* respectively. The anchor is preferably formed from a rectangular bar of good steel as for example having about .60% carbon content, bent by suitable die pressing or forging processes into a body having an intermediate downwardly bowed portion forming a main body bend 1, with a lateral rail base-contacting portion 2 on one side, and a second rail base-contacting portion 3 on the other side of the bend 1, with a supplementary downwardly and outwardly bent portion forming a bend 4 beyond the rail-contacting portion 3, and a supplementary downwardly and outwardly bent portion forming a bend 17 beyond the rail-contacting portion 2. Beyond the bend 4 the end of the anchor is turned up to form a terminal or neck 5, hereinafter referred to as the free end of the anchor. This end extends upward and outward forming an inner cam face 6, in which is a transverse notch or recess N. The contacting portions 2 and 3 are located between bends in the anchor body, and are adapted to contact with the under face of the rail base at points symmetrically disposed, near but not at the edges of the rail base.

The other end of the anchor is formed into a hook H, by a vertical upwardly extending portion 7, and an inturned end or terminal portion 8, as illustrated. This end of the anchor for convenience may be referred to as the hooked end.

The anchor is formed from the blank to

final form by a succession of die forging of pressing operations during the course of which the metal in the base-contacting portions 2 and 3 is preferably pressed so as to 5 thicken the bar progressively from the rear edges to the forward edges of those portions, as illustrated in Fig. 3, this thickening being distributed so as to form the upper surfaces of the portions 2 and 3 into slightly flattened 10 forwardly-rising faces, respectively, as illustrated. That is to say, these surfaces are inclined with respect to a perpendicular to the planes of the sides of the anchor body. This is for the purpose of bringing the forward 15 edges *a* and *b* only of the portions 2 and 3 into contact with the bottom of the rail, under operating conditions, as illustrated in Figs. 1, 2 and 3. By the forward edge of 20 the anchor and of the portions 2 and 3, etc., as used in this specification and the claims, is meant the edge on the side of the anchor in the direction from which the rail tends to 25 creep. In other words the forward edge of the anchor is positioned toward the rear of the creeping rail.

The notch or recess *N* is formed by a substantially vertical face 9, and a cooperating upper meeting face 10 sloped to conform with and seat upon the upper face of the rail base *y* when the anchor is in normal position 30 thereon. The upper face 10 of the notch as shown in Figs. 2 and 3 extends obliquely across the cam face 6 of the free end 5 of the anchor. The under rail-engaging face 12 of 35 the terminal portion 8 is sloped to conform with the upper surface of the rail base *x*, so that it may seat directly thereon when the anchor is applied. The face 12 is in longitudinal alignment with the face 10 of the notch *N*, so that when the anchor is applied 40 to a rail it will be thrown by resiliency of the anchor through contact of the portion 7 and obliquely positioned face 12 of the hook and by the face 9 and obliquely positioned face 45 10 of the notch *N* with the respective corners of the rail base, into the normally canted position shown in Fig. 1. The resulting canting position of the anchor as the face 10 50 snaps onto the rail corner throws the faces *a* and *b* into contact with the bottom of the rail, as shown in Figs. 2 and 3. Similar means for canting the anchor is used in anchors C, D, E, and F, below referred to, with modifications.

55 The anchor A is applied by moving it transversely under a rail until the hook H engages the edge of the rail base *x* and the inner upper corner 13 of the free end of the anchor passes the lower corner 14 of the rail base *y*. Thereafter an upward force exerted 60 underneath the free end of the anchor, as for example by a crowbar, causes the cam face 6 to ride upward against the side edge of the rail base *y*, the end 5 being forced outward thereby, until the notch *N* is reached

by the upper corner 15 of the rail base. Thereupon the upper face 10 of the notch will ride up on the upper side of the rail base *y* and a positive engagement of the notch and rail base will result. The oblique 70 relation of face 10 will as it snaps over the rail base corner cant the anchor, bringing the edges *a* and *b* into engagement with the rail base.

The distance between face 9 of the free end 75 and the opposed inner face of the hooked end of the anchor is slightly less than the width of the rail base, so that when the anchor is applied there is a firm grip and contact of the anchor on the edges of the rail 80 base. This is not depended on, however, for the effective holding of the rail, as will be apparent.

In this upward movement of the free end 85 5 of the anchor the forward edge *a* of the rail-contacting portion 2 is not adapted to be brought into contact with the under side of the rail to any substantial degree until the anchor is canted by final engagement of notch *N*. Consequently there is no fulcrum 90 ing as between the upper rail-contacting face 12 on top of the rail and the portion 2 on the under side of the rail base *x*. The same is true as to the portion 3 and face 10 of the notch.

The necessary resiliency for allowing the anchor to be sprung to position is supplied by the anchor body in the bends 17, 1, and 4.

In normal seated position the anchor is 100 positively seated on the upper sides of the rail base at each end, and is in edge contact with the under side of the rail base at two places intermediate the rail edges. These two edge contacts are preferably at the two forward contacting edges of the anchor under the rail, these contacts being preferably made and temporarily maintained by distortion within the elastic limits of the metal 105 of the anchor body.

The rail R is normally seated upon a tie 110 plate P, which in turn rests upon a cross tie T, as illustrated in Fig. 3. When the rail moves relative to the tie from the left as indicated by the arrow in Fig. 3, the bow 115 1 of the anchor is carried against the side of the tie and any further movement of the rail results in an abutment at a point below the plate P, of the anchor and tie. This tends to increase the canting of the anchor, causing a fulcruming of it in such canting 120 movement against the under side of the rail at the forward edges *a* and *b* of the anchor, and on top of the rail at the rear edges of faces 10 and 12, as illustrated in Figs. 1 125 and 3. The anchor being of hard steel, preferably heat treated after forming to increase the hardness, and having line-contacts with the under side of the rail base as illustrated, will take a very secure biting grip on the rail, the resistance to creeping of 130

the rail actually increasing with pressure of the creeping tendency. The grip of this form of anchor depends on this casting action of rail movement to give the desired resistance, since the resiliency of the anchor itself is used only for securing and maintaining the proper positioning of the anchor on the rail. At the same time on such a canting tendency the faces 10 and 12 that seat on top of the rail base will tend to score the upper face of the rail at their rear edges, as will be apparent.

Preferably, as above stated, in the die forming processes used in making these anchors, the portions 2 and 3 of the anchor shown in Fig. 2, and of the corresponding portions of the anchors shown in Figs. 4, 6, 9 and 10 are made with slightly flattened inclined upper faces, sloping upward to the forward edge thereof, as illustrated in Figs. 7, 8, and 11. By so doing a greater inclination of the lower contacting faces of the anchor with respect to the under side of the rail is secured, and a longer line of biting contact with the lower face of the rail, and consequently a more resistant grip of the anchor on the rail. However, it will be apparent that by leaving the bar in its original rectangular shape, without either flattening out the tops of anchor portions 2 and 3, or changing the uniform thickness of those portions in any way, by securing a normally canted position because of the inclination of the upper base engaging faces at the ends of the anchor, there will be secured a line contact at the forward edge of the anchor with the under side of the rail. It is desirable in this latter case to cant the anchor at initial position more than where contact with the under rail face is formed by inclined faces on the portions 2 and 3 of the anchor.

The provision of the bends 1, 4, and 17, in the anchor body are important though the proportions are not critical. The main bend 1 extends downward a considerable distance, and forms an effective abutment for engaging a cross tie. In addition the metal in this bend arranged as illustrated, furnishes a resilient body for the anchor, permitting sufficient distortion or straightening out thereof for bending or pulling the free end of the anchor outward to permit it to slip up over the edge of the rail and then to return to gripping position.

The supplementary bend 17 gives the necessary size and space to the hook H at the initially seating end of the anchor to permit it to be freely positioned and the anchor to be freely rotated about the hook until the notch N snaps onto the opposite edge of the rail base, and the anchor cant to normal position.

In Fig. 4 there is illustrated a modification, in that instead of the notch or recess N

in the face of free end 5^b for locking the anchor B in position upon the rail, there is provided a ridge or raised projection 20. The under face of this ridge is inclined with respect to a perpendicular between the side planes of the anchor exactly as is the upper face 10 of the notch N, and with the same result in cooperation with the similarly inclined face at the other end of the anchor of tilting the anchor slightly so as to cause the forward edges aa and bb only of the anchor to engage the under side of the rail. In other respects the construction and operation of the anchor B are similar to those of anchor A described above.

In Fig. 5 a further modification is shown in that the lower portion of the body of anchor C, which is similar otherwise to anchor A, is bent slightly rearward, so as to give a more nearly parallel contact of the side of the anchor against the tie face. This gives greater leverage for the initial canting movement of the anchor.

In Figs. 6, 7, and 8 a modified anchor D is illustrated, wherein the parts similar to corresponding parts described above in reference to anchor A are given like reference numerals as on A, followed by the suffix "d". The same system of numbering is followed with respect to all the modifications. At the rear edge of the rail-contacting portion 3^d of the anchor D, during the forging process, a lug 30 is struck up. The corner of this hump or lug is raised to such an elevation that its highest point, constituting a rounded edge or corner 31, and the forward edge bd of the anchor opposite the hump, are in substantial parallelism longitudinally with the under face 10^d of the upper rail-engaging recess N.

Consequently, the hump 30 with its edge 31 and the face 10^d, cooperate with the face 12^d in securing and holding the anchor in normal canted position when it is placed on the rail. Thus the lug 30 engages the under side of the rail on the rear side of the anchor, preventing any accidental displacement or looseness of the anchor on the rail after it is applied. In effect the lug 30 acts as a chock or wedge behind the canted anchor to prevent its rocking backward. It is not intended to have any material effect in the way of direct grip on the rail.

In Fig. 9 a further modification is illustrated in that in the anchor E both the portions 2^e and 3^e, have the rear edges struck up to form lugs 30 having contacting edges 31. Otherwise the construction of the device is substantially the same as that illustrated in Figs. 6 to 8. In fact Fig. 7 may be regarded as a corresponding section of Fig. 9 as well as a section of Fig. 6. On this case there are normally four edge contacts with the under face of the rail. As with the anchor D the purpose of the two lugs 30 in

anchor E is to prevent back tilting of the anchor on the rail.

In Figs. 10 and 11 a further modification is illustrated in that instead of the hook H as formed by the portions 2, 7 and 8 in anchor A, a terminal loop L is formed in the anchor F by extending the vertical portion 7^t upward and then inward and downward so that its end face 40 will bear upon the inclined upper face of the rail base α at a material distance from the outer edge thereof, nearly above the oppositely contacting portion 2^t. The end 40 of the loop L is shaped to lie flat upon the upper face of the rail base α , being inclined to conform thereto transversely of the rail base, and inclined longitudinally of the rail base in alignment with the wall 10^t of the notch N^t, so as, in cooperation with the said upper face of the notch to normally position the anchor in canted position, as illustrated in Fig. 11. The other portions of the anchor are constructed as described with reference to Fig. 1. There is no striking up of any lug on the rear edge of the anchor F as shown in Figs. 6 or 9, but this may be done, as and for the purposes, and with the results of such lugs as described with respect to anchors D or E, above.

The anchor F is applied, as will be readily understood, by slipping the loop L over one edge of the rail, and forcing the anchor inward by transverse movement relative to the rail, the resiliency of the metal in the loop L permitting it to open to permit the loop to pass onto the rail base α until the upper corner 13^t of the free end of the anchor passes the lower corner 14^t of the opposite edge of the rail base. Thereupon an upward forcing of the free end of the anchor, until the notch N^t snaps into engagement with the upper outer corner 15^t of the rail base, positions it upon the rail. The resiliency of the metal in the bends 1^t and 4^t and loop L permits this distortion, but brings the anchor back towards its original position as far as the dimensions of the rail base permit, resulting in a gripping of the edges of the rail base by the anchor. When this position is reached the inclined faces 40 and 10^t throw the anchor to canted position on the rail and so bring the forward edges af and bf into contact with the under side of the rail.

Figs. 12, 13 and 14 show another modification, the anchor G being adapted to be seated in a plane perpendicular to the axis of the rail and to contact with the under side of the rail base on opposite edges of the two contacting portions 2^g and 3^g, respectively.

The metal in the portions 2^g and 3^g, adapted to contact with the under side of the rail, is reformed in the die processes so as to incline the upper surface of the portion 2^g to-

wards one edge of the anchor, and the portion 3^g towards the opposite edge of the anchor. The faces 10^g, 12^g adapted to seat on the upper faces of the rail base are not oblique to the plane of the sides of the anchor as in anchor A, but on the contrary are perpendicular to those planes. When the anchor is positioned as shown in Fig. 12 it is intended to contact with the upper side of the rail on the faces 10^g, 12^g, and at the opposite edges ag and bg of the portions 2^g, 3^g, respectively.

The result of this construction is that this anchor may be put on a rail either end to, without change of function. That is to say it is reversible. Movement of the rail to cause the anchor to abut the tie will tend to cant it, whereupon the edge of the anchor underneath the rail on the forward side of the anchor will tend to bite into and so to secure a positive grip on the under side of the rail and increase resistance to passage of the rail through the anchor. This construction of anchor results in a device that can be put on by unskilled labor without danger of being wrongly placed. Furthermore, after the anchor G has been in use for a considerable time on a one-way track, it may be taken off and reversed, largely with the effect of a new anchor, so far as presenting a sharp rail base gripping contact is concerned.

By the constructions above described I am enabled to secure a one-piece resilient rail-gripping anchor, comprising an upper and a lower gripping contact on each side of the rail base, adapted to be positioned upon the tie by distortion of the metal during the positioning movement, and designed to have the grip on the rail increased and made effective by the canting moment produced by movement of the rail relative to the anchor, the anchor being limited in travel as a whole by abutment with a stationary tie. Many disadvantages of anchors of two-piece construction, and of one-piece anchors depending on a clamping or jaw grip on the rail base dependent upon resiliency of the anchor body, are avoided. The present anchor depends on resiliency of the anchor body for positioning only, and thereafter functions by rigidity of the anchor due to the grip produced by canting of the anchor by movement of the rail.

I claim:

1. A one-piece resilient rail anchor adapted to extend under and to engage the base of the rail and to be retained thereon by resiliency of the anchor body, comprising terminal abutments adapted to engage the upper sides of the rail base on each side of the web, one end of the anchor being formed into an inclined cam face above one of said abutments, and cooperative intermediate portions adapted to engage the under side of the rail base near each side thereof, whereby each

- side of the rail base may be engaged between an upper and a lower contacting portion of the anchor and the anchor may be positioned by a turning movement about the 5 end first applied to the rail.
2. A one-piece resilient rail anchor adapted to extend under and to engage the base of a rail and to be retained thereon by resiliency of the anchor body, comprising terminal 10 portions adapted to engage the upper sides of the rail base on each side of the web, and two cooperating intermediate portions adapted to engage the under side of the rail base, the body of the anchor between the said 15 terminal portions and the said intermediate portions being formed into bends out of contact with the under side of the rail, said intermediate portions being adapted to engage the under side of the rail at their edges only, 20 whereby each side of the rail base may be engaged between an upper portion and the edge of a lower contacting portion of the anchor.
3. A resilient one-piece rail anchor adapted 25 to extend under and to engage the base of a rail, comprising upwardly extending terminal portions with inturned projections adapted to seat on the upper faces of the rail base, the anchor body extending from said 30 terminal portions respectively straight downwardly beyond the rail base and adapted to contact with the side faces of the said base throughout and then extending inward and upward to form intermediate portions 35 adapted to engage the rail on the under side of the base and then downward and inward to form an intermediate enlarged bend or yoke between the said intermediate engaging portions.
4. A one-piece anchor adapted to be retained upon a rail base by its own resiliency, comprising a hook at one end adapted to engage the upper side of the rail, an adjacent portion in the body of the anchor adapted 45 to contact with the under face of the rail, an enlarged bend in the anchor body beyond said base-contacting portion, a second portion adapted to contact with the under side of the rail, the anchor beyond said second contacting portion being bent downward and 50 then upward to form a free end having an inclined cam face, a rail-base-engaging abutment across said cam face, whereby when the hook portion engages one side of the rail 55 the other end of the anchor may be forced upward to cause the cam face to contact with the other edge of the rail and then to ride upward and outward thereon until the said abutment engages the upper outer corner 60 of the rail and locks the anchor in position on the rail.
5. A rail anchor substantially as described in claim 1, characterized by the fact that the intermediate portions are adapted to engage the under side of the rail base only at the 65 edge of the anchor.
6. A rail anchor substantially as described in claim 1, characterized by the fact that each of the said intermediate portions has its rail contacting face inclined toward the 70 forward edge of the anchor so as to engage the under side of the rail with line contacts.
7. A rail anchor substantially as described in claim 2, characterized by the fact that between the two portions adapted to engage the 75 under side of the rail the body of the anchor is formed into a resilient depending bend.
8. A rail anchor substantially as described in claim 1, characterized by the fact that one end of the anchor is adapted to hook over one edge of a rail and the free end comprises an inclined face having a transverse abutment thereacross adapted to engage and seat upon the upper corner of the rail base upon upward movement of the free end of the anchor after bringing the said inclined face against the edge of the rail base. 80
9. A rail anchor substantially as described in claim 1, characterized by the fact that the portions thereof adapted to seat on the upper 90 sides of the rail base are obliquely positioned with respect to perpendicularly to the planes of the sides of the anchor, and the portions adapted to seat on the under side of the rail are raised toward their forward edges, whereby the anchor is normally held in a canted position on the rail with only its forward edge in contact with the under side of the rail. 95
10. A rail anchor substantially as described in claim 4, characterized by the fact that the portions thereof adapted to seat on the upper 100 sides of the rail base are obliquely positioned with respect to perpendicularly to the planes of the sides of the anchor and the portions adapted to seat on the under side of the rail are raised toward their forward edges, whereby the said intermediate portions are adapted by canting of the anchor to be brought into 105 contact with the under side of the rail at their forward edges only. 110
11. A rail anchor substantially as described in claim 4, characterized by the fact that the upper rail-engaging face of said hooked end and the abutment in said inclined face of the free end are in parallel alignment longitudinally and inclined with respect to the side faces of the anchors, whereby to seat the anchor in canted position on the rail. 115
12. A rail anchor substantially as described in claim 4, characterized by the fact that a lug is placed in the rear edge of the intermediate contacting portion near the cam-faced end, said lug being adapted to bear against the under face of the rail when the anchor is in normal canted position. 120
13. A rail anchor substantially as described in claim 4, characterized by the fact that a

lug is struck up in the rear edge of each intermediate contacting portion, said lugs being adapted to bear against the under face of the rail when the anchor is in normal canted position.

14. A rail anchor substantially as described in claim 3, characterized by the fact that the lower portion of the body comprised in the said depending bend is bent rearwardly out 10 of the median plane of the upper portions of the anchor body.

15. A rail anchor substantially as described in claim 1, characterized by the fact that at one end the anchor terminates in a loop that 15 extends above the rail edge and has its end adapted to seat on the upper side of the rail a substantial distance from the rail edge.

16. A rail anchor substantially as described in claim 1, characterized by the fact that at 20 one end the anchor terminates in a loop that extends above the rail edge and at its end is adapted to seat on the upper side of the rail a substantial distance from the rail edge, said loop terminating in a face shaped to 25 seat on the sloping upper side of the rail face and inclined longitudinally of the anchor, whereby to hold the anchor in canted position upon the rail.

17. A rail anchor adapted to engage the 30 base of a rail and to be held thereon by its own resiliency, one end of the anchor being turned back to positively seat upon the upper side of the rail base, the other end being adapted to be sprung outward to pass upward past the other edge of the rail base 35 after the first mentioned end of the anchor is seated and having a notch therein to engage the upper corner of the rail base, said notch being positioned obliquely across the 40 inner anchor face, whereby the anchor is held with its forward edge only in contact with the under side of the rail base.

18. A rail anchor adapted to engage by its inherent resiliency the base of a rail, having 45 its ends bent upward and inward to seat on top of the rail base, provided with an abutment in one of said ends adapted to engage the upper corner of the rail base whereby to hold the anchor in a plane oblique 50 to the vertical plane perpendicular to the

axis of the rail and so to engage the under side of the rail with the edge only of the anchor.

19. A one-piece rail anchor adapted to extend under a rail and to be retained on the base 55 thereof, having a plurality of faces adapted to engage the underside of the rail at points spaced inward from the edges of the rail and at the forward edges only of the faces, and means to hold the anchor with 60 the edges in engagement with the underside of the rail.

20. A rail anchor adapted to extend under a rail and to be retained on the base 65 thereof, having a plurality of inclined intermediate faces formed by bends in the anchor and adapted to engage the underside of the rail at the forward edges of the faces, and integral means to hold the anchor with the 70 said edges in engagement with the underside of the rail.

21. A rail anchor adapted to be held in engagement with the base of a rail by its own resiliency, the anchor having a plurality 75 of faces formed by bends in the anchor adapted to engage the underside of the rail, and integral means to hold the anchor in position with the said inclined portions engaging the underside of the rail at their forward edges only.

22. A rail anchor adapted to be held in engagement with the underside of a rail by its own resiliency, the anchor having inclined faces adapted to engage the underside 85 of the rail, and means to hold the anchor in position with the said inclined faces engaging the underside of the rail at their forward edges only.

23. A rail anchor adapted to engage at each end the upper corners of the base of a rail, 90 one end of the anchor having a rail base engaging abutment adapted to engage the upper corner of the rail and shaped to hold the anchor at an oblique angle to the plane of the base of the rail, whereby to press the forward edge only of the anchor against the lower face of the rail.

In testimony whereof, I sign my name.

EMANUEL WOODINGS.
